United States Patent Office

Des. 218,510
Patented Aug. 18, 1970

218,510

PORTABLE CARRIER FOR MOTORCYCLES

Cecil E. Gwin and Harvey L. Gwin, both of 9400 Lake
Natoma Drive, Orangevale, Calif. 95662

Filed May 21, 1969, Ser. No. 17,260

Term of patent 14 years

Int. Cl. D12—14

U.S. Cl. D90—18

Fig. 1

Fig. 2

Fig. 3

Fig. 4

FIG. 1 is a top plan view of a portable carrier for motorcycles showing our new design;

FIG. 2 is an elevational view of one side, the opposite side being substantially similar in appearance;

FIG. 3 is a front elevational view; and,

FIG. 4 is a rear elevational view.

We claim:

The ornamental design for a portable carrier for motorcycles, as shown and described.
